United States Patent

Des. 235,178
Patented May 27, 1975

235,178

CHAIR

Morris F. Fisher, Carmel, Ind., assignor to Mohasco Corporation, Amsterdam, N.Y.

Filed July 23, 1973, Ser. No. 382,091

Term of patent 14 years

Int. Cl. D6—01

U.S. Cl. D6—49

The figure is a perspective view of a chair illustrating my new design.

The back of the chair is conventionally plain while the side not shown is substantially identical to the side shown.

I claim:

The ornamental design for a chair, as shown and described.
